LUBRICATING APPARATUS

Henry R. Welby, Detroit, Mich., assignor to Detroit Lubricator Company, Detroit, Mich., a corporation of Michigan

Application March 28, 1940, Serial No. 326,462

8 Claims. (Cl. 184—55)

My invention relates generally to lubricating apparatus and more particularly to apparatus for lubricating the internal walls of a reciprocating type steam engine.

One object of my invention is to provide means for supplying oil to the cylinder of a steam engine.

Another object is to provide means for admitting the oil solely into the portion of the cylinder which is in the working phase.

Another object is to provide means for operating the admitting means by the steam pressure of the cylinder portions.

Another object is to provide means for rapidly blowing the oil admitted by the admitting means into the cylinder.

The invention consists in the new and novel parts and arrangement thereof, the novelty of which will be particularly pointed out and distinctly claimed.

In the accompanying drawings, to be taken as a part of this specification, I have fully and clearly illustrated a preferred embodiment of my invention, in which drawings—

Fig. 1 is a side view in elevation showing my control apparatus affixed to a portion of a locomotive;

Fig. 2 is an end view of my control apparatus secured to a portion of a locomotive;

Fig. 3 is a view of the control apparatus and taken substantially along the line 3—3 of Fig. 2 looking in the direction of the arrows;

Fig. 4 is a view taken substantially along the line 4—4 of Fig. 3 looking in the direction of the arrows;

Fig. 5 is a view taken substantially along the line 5—5 of Fig. 3 looking in the direction of the arrows;

Fig. 6 is a view taken substantially along the line 6—6 of Fig. 3 looking in the direction of the arrows;

Fig. 7 is a diagrammatic view of a portion of a steam engine including the steam controlling valve and the power cylinder, and of the lubricant flow controlling means connected thereto, with the members in position just after the start of a power stroke or for movement of the piston to the left;

Fig. 8 is a diagrammatic view similar to that of Fig. 7, showing the position of the members just prior to the completion of the movement of the piston to the left, and showing the flow controlling means in a transitory position while moving to the right;

Fig. 9 is a diagrammatic view similar to that

of Fig. 7, but showing the position of the parts an instant later than the showing in Fig. 8, with the flow controlling means in its position for supplying oil to the left end of the cylinder;

5 Fig. 10 is a diagrammatic view similar to that of Fig. 7, but showing the position of the engine parts during the power stroke of the piston when it is moving toward the right, and of the flow controlling means for supplying oil to the left end of the cylinder;

Fig. 11 shows a representative steam indicator card for both portions of the power cylinder and showing the operation of the lubricant flow controlling means;

15 Fig. 12 is a view in horizontal cross-section showing a modified form of my flow controlling means and with the members shown in a position similar to the showing of Fig. 8, and

Fig. 13 is a view in vertical cross-section showing the steam connection to the oil supply line of the modified controlling means.

Referring to the drawings by characters of reference, the numeral 1 designates generally my oil controlling apparatus or means having an oil inlet 2, steam inlets 3, 4 and steam atomized oil outlets 5, 6. The inlets 3 and 4 are connected

25 by means of conduits or tubes 3^a, 4^a to the cylinder live steam supplying conduits or passageways 3^b, 4^b. The inlet 2 is screw-threadedly secured to one end of a pipe nipple or conduit portion 7 which has its other end connected to the outlet 7^a of a pressure sensitive oil line check valve 8. The check valve 8 is any of the well

30 known types and may be similar to that shown in Letters Patent 1,843,068, granted January 26, 1932, to Adolf von Wangenheim et al. The nipple 7 extends through an aperture in a horizontal arm 9 of a supporting member 10 secured as

35 by bolts to a wall of the main or power cylinder 11. A nut 12, threaded externally to the nipple 7, is clamped tightly to one face of the arm 9 and holds a shoulder of the valve 8 against the other face of the arm 9 to rigidly mount the control apparatus 1 and the valve 8. Oil under

40 pressure from a suitable force feed mechanical lubricator, such as is shown in either of the Letters Patents 1,959,698, dated May 22, 1934, or 1,991,340, dated February 12, 1935, each granted to Adolf von Wangenheim, is supplied to the valve 8 through a conduit 13, and flows upward through the valve outlet 7^a and nipple 7 into the control apparatus 1 where it is discharged

45 through the outlets 5, 6 into conduits 14, 15 for transmission to the left and right ends 16, 17, respectively, of the power cylinder 11. The steam

50 valve 8 through a conduit 13, and flows upward through the valve outlet 7^a and nipple 7 into the control apparatus 1 where it is discharged through the outlets 5, 6 into conduits 14, 15 for transmission to the left and right ends 16, 17, respectively, of the power cylinder 11. The steam

inlets 3, 4 are respectively connected by means of the conduits 3^a, 4^a to main steam supplying conduits 3^b, 4^b, respectively, supplying the left and right ends 16, 17, respectively, of the power cylinder 11.

In Figs. 3, 4, 5 and 6 the control means 1 is shown in greater detail. The means 1 comprises a casting or housing member having a horizontal cylindrical bore 22 opening through opposite ends 23, 24 thereof which are closed by nipples threadedly secured in the open ends, and which nipples form the steam inlets 3, 4. The inlet 2 leads vertically upward and opens into the bore 22 through its side wall and the opening is substantially midway between the ends 23, 24. A pair of horizontally extending passageways or conduits 26, 27 lead outward from the side wall of bore 22 and terminate in threaded portions 28, bore 29 in which are threadedly secured nipples forming the outlets 5, 6. The openings of the conduits 26, 27 into the bore 22 are spaced from the midpoint of the bore 22 toward the ends 23, 24, respectively. Reciprocally movable within the bore 22 is a cylindrical piston or plunger member 30 which, due to its tight piston-fit with the walls of the bore 22, cooperates with the side wall openings to form a slide valve. The longitudinal position of the plunger 30 within the bore 22 is determined by the relative pressure within the steam inlets 3, 4.

When the plunger 30 is in its extreme left position, as shown in Fig. 3, the opening of the inlet 2 is communicatively connected to the opening of the horizontal outlet passageway 27 by means of a recess 31 in the outer wall of the plunger 30 which, for example, might be a slot milled therein. Steam from the steam inlet 4 is also conducted to the recess 31 through a passageway 32 which has a portion opening radially outward into the recess, and has a longitudinally extending portion which may open centrally through the right end of the plunger 30. When the plunger 30 is in its position furthest toward the right, the inlet 2 is similarly connected to the horizontal outlet passageway 26 through a recess 31^a. The steam inlet 3 is connected in a manner similar to the inlet 4 to the recess 31^a by means of a passageway 32^a. The plunger 30 which operates as a slide valve therefore alternately connects the inlet 2 to the outlets 5, 6 for flow of lubricant to the cylinder ends 16, 17. The plunger 30 has a longitudinal recess or guideway 33 in its upper wall portion which receives an end or guide portion of a cap screw 34 threadedly secured within an aperture through the top wall of the bore 22, and the guideway 33 and guide portion of screw 34 cooperate to prevent axial rotation of the plunger 30 within the bore 22 thereby to maintain the recesses 31, 31^a in correct cooperative relation with the openings through the side walls of the bore 22.

For the purpose of safety, in case the plunger 30 should stick in a midposition, the plunger is recessed, as at 35, so that the opening of the inlet 2 is communicatively connected to each of the horizontal passageways 26, 27 for supply of oil to both the cylinder ends 16, 17.

In Figs. 7, 8, 9 and 10 for the sake of simplicity and convenient showing of the operation of the control means 1, the control means 1 and the valve 8 are shown as if cast directly in a web 50 connecting a steam chest 51 with the main power cylinder 11. The preferred commercial embodiment however is that which is shown in Figs. 1 to 6 in which the valve 8 and the means 1 form

an independent unit mounted externally of the cylinder 11 and of the steam chest 51. The steam chest 51 is shown as having a live steam inlet 52 for connection to a suitable steam generator such as a boiler which supplies the live steam through a suitable throttle valve (not shown) to the inlet chamber 53 of the steam chest 51 formed intermediate two interconnected piston-like slide valves 54, 55. The valves are operated by means of a plunger or rod 56 which is in turn operated by suitable mechanism in the usual manner so that the valves 54, 55 are moved to open ports 57, 58 to the steam inlet chamber 53 or to exhaust chambers 59, 60 for control of the steam flow through the passageways 3^b, 4^b in the usual manner. The piston 61 has a thrust rod 62 for transmitting work to a locomotive drive wheel or other power applying means (not shown) driven by the piston 61.

The valve means 8 is shown as having a pressure sensitive diaphragm 63 which carries a valve element 64 and which is biased to urge the element 64 against its seat and into valve closed position. The biasing of the diaphragm 63 is such that it will not open the valve element 64 to flow until the pressure of the oil within a chamber 65 of valve means 8 is above the maximum pressure of the steam within the passageways 3^b, 4^b. Upon the given oil pressure being attained within the chamber 65 the pressure acts on the diaphragm 63 to move the valve element 64 from its seat to allow oil to flow to the inlet 2 of the control means 1.

In Figs. 12 and 13 there is shown a modification of the control means 1 in which a separate steam line 65^a which is in constant communication with the main line steam supply 65^b either ahead of or after the main throttle valve (as shown) is connected to a horizontal passageway 66 which does not open into the bore 22 but opens through a small diameter bore 67 into the inlet 2 adjacent its opening to the bore 22 so that as the oil is admitted to the bore 22 and recesses 31, or 31^a, the steam supplied to passageway 66 will blow the oil through the conduits 26 or 27 into the cylinder ends 16 or 17. A shut-off valve 68 may be placed in the steam line to the control means 1 so that during idle periods of the engine the flow of steam to the means 1 may be discontinued. Passageways 32 and 32^a are omitted in the modified form of the means 1.

The operation of the control means 1 may best be seen in Figs. 7, 8, 9 and 10 which show four different positions of engine operation and which is as follows: In Fig. 7 the piston slide valve 54 is open to allow the spent steam in the cylinder end 16 to exhaust and the piston slide valve 55 has opened the passageway 4^b for flow of live steam from the chamber 53 to the cylinder end 17. The live steam is acting on the piston 61 and moving it toward the left so that it is uncovering the opening of the conduit 15 into the cylinder end 11. The plunger 30 is already at the extreme left end of the bore 22 so that the inlet 2 of the control means 1 is communicatively connected by means of the recess 31 to the conduit 15. The oil, which is admitted to the inlet 2 by the valve element 64, is flowing in the recess 31 where it is picked up by the steam which flows from the passageway 4^b, conduit 4^a, passageway 32 and into recess 31 from whence it is blown in an atomized condition through conduit 15 into the cylinder end 11.

Steam is continually admitted through passageway 4^b until the piston 61 has moved toward

the left a predetermined amount, which is determined in the usual manner and well known to those skilled in the art, at which time the slide valve 55 closes and the normal expansion of the steam, with decrease in temperature and pressure occurs. Shortly after the live steam has been cut off by closure of the slide valve 55, the slide valve 54 moves to a position to close the passageway 3^b to the exhaust chamber 59. Fig. 8 shows the position of piston 61 after the slide valve 54 has closed the passageway 3^b to the steam chest 51 and the slide valve 55 has opened the passageway 4^b for exhaust of the steam within the cylinder end 17 to the exhaust chamber 60. The valve 54 being closed and the piston 61 having continued movement toward the left, the pressure within cylinder end 18 and passageway 3^b increases and since the pressure within passageway 4^b and the cylinder end 17 is low, due to the open slide valve 55, the plunger 30 will be moved toward the right end of the bore 22 and will for an instant be in the position shown in Fig. 8. Almost immediately however, the plunger 30 will under normal operation move to the position shown in Fig. 9. In this position it will be noted the piston 61 is in substantially the same position as in Fig. 8, but in reality the piston 61 has moved slightly toward the left. The trapped steam within the cylinder end 16 and passageway 3^b acts to cushion the piston 61 as it reaches the end portion of its travel.

In Fig. 10 the piston 61 has already reached the extreme left position and is moving toward the right under the effect of the live steam which is being admitted through the slide valve 54. The piston 61 is already beyond the opening of the conduit 14 into the cylinder end 16, and oil from the inlet 2 flows to the recess 31^a from whence it is blown by steam admitted to the recess 31^a by means of the passageway 32^a and the conduit 14 into the cylinder end 16. As the piston 61 approaches the right end of the cylinder 11, the same relative sequence of operation would occur as occurred at the left end, and each subsequent stroke of piston 61 will cause a repetition of the described operation.

Fig. 11 shows a sample "steam indicator card" of a steam cylinder in which the position of piston 61 in relation to steam pressure within the cylinder end 16 is shown in full line and to which reference is made to bring out more in detail the operation of the oil controlling means 1. The openings of the atomized oil conduits 14, 15 for the most satisfactory operation are located in the walls of the cylinder 11 so that they are closed by the piston 61 until the piston has moved a predetermined distance away from one end. The reference character A indicates the position of the piston 61 at the time the valve 54 opens to admit live steam to cylinder end 16. Point B indicates the position of piston 61 when the piston has moved toward the right a distance sufficient to open the outlet of the conduit 14. Point C indicates the point at which the valve 54 cuts off the flow of live steam steam to the cylinder end 16, while points D and E indicate the opening and closing, respectively, of the valve 54 to exhaust the spent steam from the cylinder end 16. It will be noted that the position of the opening of conduit 14 is so arranged relative to a normal steam and piston cycle that the piston 61 does not act to uncover the opening of conduit 14 until the piston is well on its way in a power stroke to the right, under the influence of steam admitted by the valve 54, and which opening it will be noted

is closed by the piston 61, when moving toward the left, prior to the normal opening by the plunger 30 of conduit 14. On movement of the piston 61 on a power stroke, steam under a pressure which is at least sufficient to move the piston 61 against the opposing force exerted by the rod 62, moves the piston 61 toward the right and the volume of the cylinder end 16 increases which is immediately filled with live steam which is admitted through the valve 54 and passageway 3^b. As is well known to those skilled in the art, flow of a fluid through a conduit or passageway is accompanied by a drop in pressure of the fluid as it passes therethrough, which in any given conduit varies with the rate of fluid flow. Therefore, it may now be seen that there will be a difference of pressure between the point at which the conduit 3^a opens into the passageway 3^b and the pressure within the cylinder end 16. This difference in pressure causes steam to flow through conduit 3^a, passageway 32^a, recess 31^a, and conduit 14 to the cylinder end 16. The steam flow so caused atomizes the blows any oil into the cylinder end 16 which may be admitted to the recess 31^a from the inlet 2. On the return stroke or movement of piston 61 to the left, the piston 61 moves to a position closing the conduit 14 to flow prior to movement of the plunger 30 to open the conduit 14 to flow. Movement of plunger 30 to the right occurs when the steam pressure condition and the position of piston 61 is that indicated at F, and which position is as stated above subsequent to closing of the opening of the conduit 14, point G, by the piston 61. The flow through the conduit 14 is therefore always in the direction toward the cylinder end 16, and is of sufficient magnitude to blow any oil admitted to recess 31^a into the cylinder end 16. The cylinder end 17 has a "steam chart" shown in dash-dot lines and which is similar in form to that shown in full line for the end 16 except that the point A' of the dash-dot chart appears at the right side and point D' appears at the left side because as the cylinder end 16 is exhausting, the cylinder end 17 is in the power stroke. It may now be seen that due to the action of the relative pressures within the cylinder ends 16 and 17 acting on the end walls of the plunger 30, the plunger 30 is moved to the left to close the conduit 14 and to open the conduit 15 at the point H which is identical in piston position with point F' as shown by the vertical line b. The vertical line a which extends through the points H' and F indicates that both points occur at the same position of the piston 61. The control means 1 admits oil or other lubricant into the working cylinder end and only during the power stroke, and therefore a smaller amount of oil is necessary to lubricate the piston. Not only is this advantageous from an economy standpoint, but it also reduces the formation of carbon on the cylinder heads and exhaust stacks and results in greater operating economy.

In the event that the plunger 30 should stick in the position shown in Fig. 8, the passageway or recess 35 will communicatively connect the inlet 2 with each of the conduits 14 and 15 and will flow to both of the cylinder ends 16 and 17.

The operation of the modification of the means 70 as shown in Figs. 12 and 13 is substantially the same as that described, with the exception that the steam used to blow in the oil is admitted into the inlet 2 directly from the live steam line either before or after the throttle instead of being admitted from the steam passageways 3^b, 4^b and

through the plunger 30 end walls. It will be evident that the advantages hereinbefore set forth will be equally applicable to the operation of the modification.

What I claim and desire to secure by Letters Patent of the United States is:

1. A lubricating apparatus for a piston of a reciprocating steam engine comprising a working cylinder, a working piston reciprocable in said working cylinder, a steam conduit connected to one end of said working cylinder, a steam conduit connected to the other end of said working cylinder, a steam valve controlling flow through and determining high pressures alternately in said steam conduits, an oil conduit opening into said one end of said working cylinder, an oil conduit opening into said other end of said working cylinder, piston operated valve means having two positions and determining alternate flow through said oil conduits, said piston operated valve means being so constructed and arranged that it is operable in one position to provide oil flow to said first-named oil conduit and to cut off oil flow to said second-named oil conduit when said working piston is at said one end of said working cylinder, said piston operated valve means being so constructed and arranged that it is operable in the second position to cut off oil flow to said first-named oil conduit and to provide oil flow to said second-named oil conduit when said working piston is at said other end of said working cylinder, a pressure conveying conduit leading from said first-named steam conduit on the working cylinder side of said steam valve and connected to one side of said piston operated valve means so that pressure in said first-named steam conduit will move said piston operated valve means to said one position, and a pressure conveying conduit leading from said second-named steam conduit on the working cylinder side of said steam valve and connected to the other side of said piston operated valve means so that pressure in said second-named steam conduit will move said piston operated valve means to said second position.

2. A lubricating apparatus for a piston of a reciprocating steam engine comprising a working cylinder, a working piston reciprocable in said working cylinder, a steam conduit connected to one end of said working cylinder, a steam conduit connected to the other end of said working cylinder, a steam valve controlling flow through and determining high pressures alternately in said steam conduits, an oil conduit opening through a side wall of said one end of said working cylinder within the range of travel of said working piston so that said working piston is operable to control flow through said conduit, an oil conduit opening through a side wall of said other end of said working cylinder within the range of travel of said working piston so that said working piston is operable to control flow through said second-named oil conduit, piston operated valve means having two positions and determining alternate flow through said oil conduits, said piston operated valve means being so constructed and arranged that it is operable in one position to provide oil flow to said first-named oil conduit and to cut off oil flow to said second-named oil conduit when said working piston is at said one end of said working cylinder, said piston operated valve means being so constructed and arranged that it is operable in the second position to cut off oil flow to said first-named oil conduit and to provide oil flow to said second-named

oil conduit when said working piston is at said other end of said working cylinder, a pressure conveying conduit leading from said first-named steam conduit on the working cylinder side of said steam valve and connected to one side of said piston operated valve means so that pressure in said first-named steam conduit will move said piston operated valve means to said one position, and a pressure conveying conduit leading from said second-named steam conduit on the working cylinder side of said steam valve and connected to the other side of said piston operated valve means so that pressure in said second-named steam conduit will move said piston operated valve means to said second position.

3. A lubricating apparatus for a piston of a reciprocating steam engine comprising a working cylinder, a working piston reciprocable in said working cylinder, a steam conduit connected to one end of said working cylinder, a steam conduit connected to the other end of said working cylinder, a steam valve controlling flow through and determining high pressures alternately in said steam conduits, an auxiliary cylinder, means for supplying oil to said auxiliary cylinder, an oil conduit leading from said auxiliary cylinder and opening into said one end of said working cylinder, an oil supplying conduit leading from said auxiliary cylinder and opening into said other end of said working cylinder, a piston valve member reciprocable in said auxiliary cylinder to two positions and determining alternate flow from said oil supplying means to said oil conduits, said piston valve member being so constructed and arranged that it is operable in one position to provide oil flow from said oil supplying means to said first-named oil conduit and to cut off oil flow from said oil supplying means to said second-named oil conduit when said working piston is at said one end of said working cylinder, said piston valve member being so constructed and arranged that it is operable in the second position to cut off oil flow from said oil supplying means to said first-named oil conduit and to provide oil flow from said oil supplying means to said second-named oil conduit when said working piston is at said other end of said working cylinder, a pressure conveying conduit leading from said first-named steam conduit on the working cylinder side of said steam valve and connected to one end of said auxiliary cylinder so that pressure in said first-named steam conduit will move said piston valve member to said one position, and a pressure conveying conduit leading from said second-named steam conduit on the working cylinder side of said steam valve and connected to the other end of said auxiliary cylinder so that pressure in said second-named steam conduit will move said piston valve member to said second position.

4. A lubricating apparatus for a piston of a reciprocating steam engine comprising a working cylinder, a working piston reciprocable in said working cylinder, a steam conduit connected to one end of said working cylinder, a steam conduit connected to the other end of said working cylinder, a steam valve determining high pressures alternately in said steam conduits, an auxiliary cylinder, means for supplying oil to said auxiliary cylinder, an oil conduit leading from said auxiliary cylinder and opening into said one end of said working cylinder, an oil supplying conduit leading from said auxiliary cylinder and opening into said other end of said working cylinder, a piston valve member reciprocable in said auxil-

iary cylinder to two positions and determining alternate flow from said oil supplying means to said oil conduits, said piston valve member being so constructed and arranged that it is operable in one position to provide oil flow from said oil supplying means to said first-named oil conduit and to cut off oil flow from said oil supplying means to said second-named oil conduit when said working piston is at said one end of said working cylinder, said piston valve member being so constructed and arranged that it is operable in the second position to cut off oil flow from said oil supplying means to said first-named oil conduit and to provide oil flow from said oil supplying means to said second-named oil conduit when said working piston is at said other end of said working cylinder, a pressure conveying conduit leading from said first-named steam conduit on the working cylinder side of said steam valve and connected to one end of said auxiliary cylinder so that pressure in said first-named steam conduit will move said piston valve member to said one position, and a pressure conveying conduit leading from said second-named steam conduit on the working cylinder side of said steam valve and connected to the other end of said auxiliary cylinder so that pressure in said second-named steam conduit will move said piston valve member to said second position, said piston valve member having a safety oil flow passageway operable to connect said oil supplying means simultaneously to said oil conduits when said piston valve member is intermediate said two positions.

5. A lubricating apparatus for a piston of a reciprocating steam engine comprising a working cylinder, a working piston reciprocable in said working cylinder, a steam conduit connected to one end of said working cylinder, a steam conduit connected to the other end of said working cylinder, a steam valve controlling flow through and determining high pressures alternately in said steam conduits, an auxiliary cylinder, means for supplying oil to said auxiliary cylinder, an oil conduit leading from said auxiliary cylinder and opening into said one end of said working cylinder, an oil supplying conduit leading from said auxiliary cylinder and opening into said other end of said working cylinder, a piston valve member reciprocable in said auxiliary cylinder to two positions and determining alternate flow from said oil supplying means to said oil conduits, said piston valve member having an oil flow passageway operable to connect said oil supplying means to said first-named oil conduit and having a shut-off portion operable to close said second-named oil conduit when said piston valve member is at one end of said auxiliary cylinder, said piston valve member having an oil flow passageway operable to connect said oil supplying means to said second-named oil conduit and having a shut-off portion operable to close said first-named oil conduit when said piston valve member is at the other end of said auxiliary cylinder, a pressure conveying conduit leading from said first-named steam conduit on the working cylinder side of said steam valve and connected to said other end of

said auxiliary cylinder so that pressure in said first-named steam conduit will move said piston valve member to said one end of said auxiliary cylinder, and a pressure conveying conduit leading from said second-named steam conduit on the working cylinder side of said steam valve and connected to said one end of said auxiliary cylinder so that pressure in said second-named steam conduit will move said piston valve member to said other end of said auxiliary cylinder.

6. In a lubricating apparatus, a hollow cylinder, a piston valve member reciprocable in said cylinder, said cylinder having an oil supply port opening intermediate the ends of and into said cylinder, said cylinder having spaced oil discharge ports opening intermediate the ends of and from said cylinder, said piston valve member having spaced passageways therethrough operable upon reciprocation of said piston valve member to connect alternately said oil supply port to said oil discharge ports, the wall of said cylinder being operable alternately to close said passageways upon reciprocation of said piston valve member, and said cylinder having steam supply ports for supplying steam to reciprocate said piston valve member.

7. In a lubricating apparatus, a hollow cylinder, a piston valve member reciprocable in said cylinder, said cylinder having an oil supply port opening intermediate the ends of and into said cylinder, said cylinder having spaced oil discharge ports opening intermediate the ends of and from said cylinder, said piston valve member having spaced passageways therethrough operable upon reciprocation of said piston valve member to connect alternately said oil supply port to said oil discharge ports, the wall of said cylinder being operable alternately to close said passageways upon reciprocation of said piston valve member, said piston valve member having a safety oil flow passageway therethrough intermediate said passageways and operable to connect said oil supply port simultaneously to said oil discharge ports, and said cylinder having steam supply ports for supplying steam to reciprocate said piston valve member.

8. In a lubricating apparatus, a hollow cylinder, a piston valve member reciprocable in said cylinder, said cylinder having an oil supply port opening intermediate the ends of and into said cylinder, said cylinder having spaced oil discharge ports opening intermediate the ends of and from said cylinder, said piston valve member having spaced passageways therethrough operable upon reciprocation of said piston valve member to connect alternately said oil supply port to said oil discharge ports, the wall of said cylinder being operable alternately to close said passageways upon reciprocation of said piston valve member, said cylinder having steam supply ports for supplying steam to reciprocate said piston valve member, and said piston valve member having aligned ports through its opposite end walls opening into said passageways to supply atomizing steam to said passageways.

HENRY R. WELBY.
